CHARGING SEAL FOR STOVES

Robert D. Lambert and Charles L. Bailey, Knoxville, Tenn., assignors to Tennessee Valley Authority, a corporation of the United States of America

Application November 18, 1943, Serial No. 510,770

6 Claims. (Cl. 126—287)

(Granted under the act of March 3, 1883, as amended April 30, 1928; 370 O. G. 757)

1

The invention herein described may be manufactured and used by or for the Government for governmental purposes without the payment to us of any royalty thereon.

This invention relates to stove construction and more particularly to seals for use during the charging and operation of such stoves.

The principal object of this invention is to provide a magazine type stove construction which will prevent the escape of mechanical particles, smoke and other products of combustion from a stove into the space around such stove during the charging of fuel into the stove. Another object of this invention is to prevent the accumulation in the fuel magazine of a stove of explosive gases resulting from the leakage of air into the fuel magazine during the normal operation of the stove. Other objects of this invention include the provision of an automatic damper arrangement which functions both during the charging and normal operation of the stove.

In the operation of stoves, particularly of the type which consists of a fuel magazine wherein the solid fuel is charged and gasified and a combustion chamber wherein the gasified fuel is burned, there is always the inconvenience and nuisance of materials escaping into the space surrounding the stove during the charging of the fuel magazine. Furthermore, during the normal operation of the stove, said leakage of air into the top of the fuel magazine may occur and the amount of this leakage may be such that when the air is mixed with some of the gasified fuel, an explosive mixture is produced and may be ignited.

The present invention is directed to an automatic charging damper for a magazine type stove having a cover to said magazine, a secondary cover adjacent thereto forming an enclosed space between said covers, and an outlet from said enclosed space communicating with a smoke channel with an outlet in the top of said magazine communicating with said smoke channel, closures for said outlets, and means associated with said secondary cover and responsive to the position of the latter to vary the position of said closures in relation to their respective outlets.

In the accompanying drawing which forms a part of the specification, and wherein reference symbols refer to like parts wherever they occur,

Fig. 1 is a vertical part-sectional view of one embodiment of the present invention applied to a heater unit having a fuel magazine and a separate combustion chamber, and

Figs. 2 to 6, inclusive, are other embodiments thereof in the same type of heater unit.

In Fig. 1, a heater unit 1, of which only the top section is shown, is composed of magazine 3, into which fuel is charged successively through openings normally closed by top cover 5 and magazine cover 7. The fuel moves slowly downward in the magazine 3, is gasified in the bottom thereof, and the gasified material burned in combustion chamber 9, with the combustion products passing from the heater through flue 11. In the normal operation of the heater 1, hinged damper arm 13, depressed by cover 5, and to which is attached counterweight 15, closes an opening communicating between magazine 3 and flue 11 with damper 17 and causes another opening communicating between the space above the top of magazine 3 and flue 11 to remain unobstructed by damper 19. In such normal operation, any of the gasified fuel which might escape through any imperfectly fitting magazine cover 7 is withdrawn through flue 11 and thereby prevents the fouling of the atmosphere around heater 1. When fuel is to be charged to magazine 3, the covers 5 and 7 are removed successively. The removal of cover 5 causes damper arm 13 to be released to position 13', and counterweight 15 to position 15', opens communication between magazine 3 and flue 11 by removal of damper 17 to position 17', and 25 closes communication between the space above magazine 3 and flue 11 with damper 19 in position 19', thereby withdrawing any gasified fuel from the top of magazine 3 through flue 11, without fouling the atmosphere around heater 1, 30 while fuel is being charged thereto.

In Fig. 2, covers 5 and 7 are connected by discharge 21. In normal operation of heater 1, hinged damper arm 23, depressed by cover 5, causes counterweighted damper 25 to close the opening communicating between the top of magazine 3 and flue 11 and causes damper 27 to be restrained from closing the opening communicating between the space above the top of magazine 3 and flue 11. Likewise, as in Fig. 1, the removal of cover 5 causes the elements to assume their respective positions 23', 25', and 27'.

In Fig. 3, hinged damper arm 29, counterweight 31, damper 33, and damper 35 are shown in normal operating position and in positions 29', 31', 33' and 35' for charging magazine 3.

In Fig. 4, hinge cover 37 and hinge cover 39 are connected by a loose linkage 41, and a damper 43, forming an integral part of the cover 39. When magazine 3 is to be charged, covers 37 and 39 are 55 raised and assume respective positions 37', 39'.

Damper 43 assumes position 43' with cover in 39' position serving to close the opening communicating between the space above magazine 3 and flue 11.

In Fig. 5, hinge cover 45 and hinge cover 47 are connected by loose linkage 41. Damper 49 and damper 51 form integral parts of covers 47 and 45, respectively. When magazine 3 is charged, covers 45 and 47 assume positions 45' and 47' and dampers 49 and 51 assume positions 49' and 51'.

In Fig. 6, sliding cover 53 and sliding cover 55 are rigidly connected by linkage 57. Hinge damper arm 59 is connected to damper 61. When magazine 3 is charged, covers 53 and 55 slide on the top of heater 1 and magazine 3, respectively, and assume positions 53' and 55'. Also, damper arm 59, damper 61, and linkage 57 assume respective positions 59', 61' and 57', wherein the linkage 57 becomes a damper for closing the opening communicating between the space above magazine 3 and flue 11.

It will be seen from the foregoing description that the present invention is directed to the combination of a coordinated pair of dampers in a magazine type stove wherein the damper at the top of the fuel magazine is closed during the normal operation of the stove, and the damper communicating with the space above the fuel magazine is open during such operation. These dampers are so associated with other elements that on the removal of the covers to the stove, the fuel magazine for charging the position of the dampers is automatically reversed. It is generally preferable to have the covers linked together for simplicity of operation. However, in certain instances this is unnecessary, since each cover may then be removed separately. In other cases, such as where the covers are removed from the openings by sliding rather than by raising, the linkage may be rigid.

It will be seen, therefore, that this invention actually may be carried out with a number of variations without departing from its spirit and scope.

We claim:

1. In a magazine heater comprising an outer shell, a combustion chamber and fuel magazine with an independent top within said shell, a top to said shell, a smoke channel through said outer shell top communicating with said combustion chamber, a fuel inlet and cover therefor in said outer shell top above said magazine, and a secondary fuel inlet and cover therefor in said independent top of said magazine below the first mentioned fuel inlet and cover, wherein the top of said magazine, the top of said shell above said magazine and the portions of said shell adjacent thereto form a zone which is enclosed except for an outlet communicating with said smoke channel with said outlet of configuration such that it may be closed or opened by the operation of a closure associated therewith; an automatic charging damper which comprises an outlet near the top of said magazine communicating with said smoke channel, closures for said outlets, and means associated with said secondary cover and responsive to the position of the latter to vary the position of said closures in relation to their respective outlets.

2. In a magazine heater comprising an outer shell, a combustion chamber and fuel magazine with an independent top within said shell, a top to said shell, a smoke channel through said outer shell top communicating with said combustion

chamber, a fuel inlet and cover therefor in said outer shell top above said magazine, and a secondary fuel inlet and cover therefor in said independent top of said magazine below the first mentioned fuel inlet and cover, wherein the top of said magazine, the top of said shell above said magazine and the portions of said shell adjacent thereto form a zone which is enclosed except for an outlet communicating with said smoke channel with said outlet of configuration such that it may be closed or opened by the operation of a closure associated therewith; an automatic charging damper which comprises an outlet near the top of said magazine communicating with said smoke channel, closures for said outlets, and means associated with said secondary cover and responsive to the position of the latter to close said magazine outlet and open the outlet to said enclosed space when said secondary cover is in place and the reverse when said secondary cover is raised.

3. In a magazine heater comprising an outer shell, a combustion chamber and fuel magazine with an independent top within said shell, a top to said shell, a smoke channel through said outer shell top communicating with said combustion chamber, a fuel inlet and cover therefor in said outer shell top above said magazine, and a secondary fuel inlet and cover therefor in said independent top of said magazine below the first mentioned fuel inlet and cover, wherein the top of said magazine, the top of said shell above said magazine and the portions of said shell adjacent thereto form a zone which is enclosed except for an outlet communicating with said smoke channel with said outlet of configuration such that it may be closed or opened by the operation of a closure associated therewith; an automatic charging damper which comprises an outlet near the top of said magazine communicating with said smoke channel, and a counterweighted, hinged damper arm and a closure for each of said outlets responsive to the movement of said arm, said arm being so shaped and positioned that it is responsive to the position of said secondary cover to close said magazine outlet and open the outlet to said enclosed space when said secondary cover is in place, and the reverse when secondary cover is raised.

4. In a magazine heater comprising an outer shell, a combustion chamber and fuel magazine with an independent top within said shell, a top to said shell, a smoke channel through said outer shell top communicating with said combustion chamber, a fuel inlet and cover therefor in said outer shell top above said magazine, and a secondary fuel inlet and cover therefor in said independent top of said magazine below the first mentioned fuel inlet and cover, wherein the top of said magazine, the top of said shell above said magazine and the portions of said shell adjacent thereto form a zone which is enclosed except for an outlet communicating with said smoke channel with said outlet of configuration such that it may be closed or opened by the operation of a closure associated therewith; an automatic charging damper which comprises an outlet near the top of said magazine communicating with said smoke channel, a linkage between said covers such that said magazine cover is responsive to the movement of said outer shell top cover, and a hinge and closure associated with the cover to said magazine so positioned as to close said magazine outlet and open the outlet to said enclosed space when said secondary cover is in place, and the reverse when said secondary cover is removed.

5. In a magazine heater comprising an outer shell, a combustion chamber and fuel magazine with an independent top within said shell, a top to said shell, a smoke channel through said outer shell top communicating with said combustion chamber, a fuel inlet and cover therefor in said outer shell top above said magazine, and a secondary fuel inlet and cover therefor in said independent top of said magazine below the first mentioned fuel inlet and cover, wherein the top of said magazine, the top of said shell above said magazine and the portions of said shell adjacent thereto form a zone which is enclosed except for an outlet communicating with said smoke channel with said outlet of configuration such that it may be closed or opened by the operation of a closure associated therewith; an automatic charging damper which comprises an outlet near the top of said magazine communicating with said smoke channel, a linkage between said covers such that said magazine cover is responsive to the movement of said outer shell top cover, and a hinge and closure associated with each cover and so positioned as to close said magazine outlet and open the outlet to said enclosed space when said secondary cover is in place and the reverse when said secondary cover is raised.

6. In a magazine heater comprising an outer shell, a combustion chamber and fuel magazine with an independent top within said shell, a top to said shell, a smoke channel through said outer shell top communicating with said combustion chamber, a fuel inlet and cover therefor in said

outer shell top above said magazine, and a secondary fuel inlet and cover therefor in said independent top of said magazine below the first mentioned fuel inlet and cover, wherein the top of said magazine, the top of said shell above said magazine and the portions of said shell adjacent thereto form a zone which is enclosed except for an outlet communicating with said smoke channel with said outlet of configuration such that it may be closed or opened by the operation of a closure associated therewith; an automatic charging damper which comprises a hinged damper arm and a closure to the outlet of said magazine responsive to the movement of the cover of said magazine, and a closure for the outlet of said enclosed zone affixed between said covers, said damper arm and said closure being so positioned as to close said magazine outlet and open the outlet of said enclosed zone when said covers are in place and the reverse when said covers are removed by sliding.
